INVENTOR
THOMAS B. ALLITT

BY *Richards, Grier*
ATTORNEYS

UNITED STATES PATENT OFFICE.

THOMAS BERRY ALLITT, OF COVENTRY, ENGLAND.

CLIP FOR ATTACHING ARTICLES OF WEARING APPAREL.

Application filed August 31, 1923. Serial No. 660,334.

To all whom it may concern:

Be it known that I, THOMAS BERRY ALLITT, subject of the King of Great Britain, residing at 89 Holyhead Road, Coventry, England, have invented certain new and useful Improvements in Clips for Attaching Articles of Wearing Apparel, of which the following is a specification.

The object of the present invention is to provide an improved and efficient form of clip for attaching, or for connecting together, articles of wearing apparel or parts thereof, such for example as securing ribbons to lingerie, to admit of their ready removal for washing or other purposes, the improved clip being neat in appearance and unobtrusive in use.

The improved clip comprises essentially two sheet metal members of an open-ended channel or trough formation, arranged with their concave or inwardly-bent faces towards one another, and having their longitudinal edges curled inwards or formed with an inwardly extending beading, the edges or sides of the one member being adapted to be engaged between the edges or sides of the other member, so that the pieces of material to be connected together are thereby clipped between the two members.

Figure 1 of the accompanying drawings shows the manner in which the improved clip or fastener is employed for securing the end of a ribbon to a camisole or other article of wearing apparel.

Figure 2 is a section on the line 2—2, Figure 1 upon a larger scale.

Figure 3 represents a perspective view of the two members of the improved clip when engaged together, but without being attached to the material.

Figure 4 shows the two members of the clip separated.

Figure 5 is a cross section on the line 5—5, Figure 3 upon a larger scale.

Figure 6 is a sectional view showing the manner in which the material is placed over the one member of the clip, prior to the engagement of the other member therewith.

The same reference numerals indicate corresponding parts in each of the figures.

Referring to the drawings, the improved clip, as described for securing the shoulder ribbons to camisoles, comprises two sheet metal members 1 and 2 of an open-ended

channel or trough-formation, the edges of the upturned sides of the member 1 being curled inwards to form a beading 3, whilst the corresponding edges of the other member 2 are curled inwards into a beading 4. The two members are disposed so that when engaged together their concave or inwardly-bent faces are presented towards one another, the member 2 being narrower than the member 1 and being arranged so that its sides snap or spring between the curled-over edges of the latter, the two members 1 and 2 being thereby detachably retained together, as shown in Figure 3. The bottom of the wider member 1 is preferably flat, its sides being bent up at equal angles to the bottom and the edges of the sides inwardly curled to form the beadings 3, as shown. The narrower member 2, on the other hand, is preferably of a shallow C-section, with its edges inwardly curled into beadings 4, as above described. This C-formation imparts an increased resilience to the sides so that a very efficient spring action is obtained, the said sides springing together when they are engaged between the sides of the wider member 1 and then expanding outwards behind the beading 3 formed by the curled-in edges of the latter.

In use the end of the ribbon 5 and the edge 6 of the camisole are laid over the concave face and curled-in edges 3 of the wider member 1 of the clip or fastener when the narrower clip member 2 is placed over the material, with its concave face downwards, immediately above the other clip member, as shown in Figure 6, its sides being then forced, by the application of sufficient pressure, between the beaded edges 3 of the latter so that the wearing apparel and ribbon is thereby rigidly clamped between the sides of the two members as shown in Figure 2, and so secured together. When the material is secured between the two clip members in this manner, the curvature of the member 2 is increased owing to the thickness of the material. The two members of the clip may be readily detached when required, thereby allowing of the ribbon 5 to be removed, when the garment is to be washed.

If desired the end of the ribbon may be engaged over the one edge only of the member 1 of the fastener, and the edge of the camisole or other garment engaged over its other edge, so that one thickness of ma-

terial only comes between the opposed edges of the two members. By curling over the edges of the sides of the two members an efficient snap action is obtained, whilst a 5 rounded gripping surface is provided so that the material is not damaged in any way.

The two members of the clip may be of any suitable cross-section provided they are 10 of an open-ended trough formation. The member 2 may, for example be of a V-section having curled-in edges.

The improved clip may also be employed for connecting together other articles of 15 wearing apparel.

Having fully described my invention,

what I desire to claim and secure by Letters Patent is:—

A clip for articles of wearing apparel, comprising two sheet metal members of an 20 open-ended channel or trough formation, disposed with their concave or inwardly-bent faces towards one another, and having their longitudinal edges curled inwards or formed with an inwardly projecting bead- 25 ing, the edges or sides of the one member being adapted to be engaged between the edges or sides of the other member, so as to clip the material between the two members.

In testimony whereof I have hereunto set 30 my hand.

THOMAS BERRY ALLITT.
